UNITED STATES PATENT OFFICE.

FRANK H. FRISSELL, OF MIDDLETOWN, CONNECTICUT, ASSIGNOR TO THE RUSSELL MFG. CO., OF MIDDLETOWN, CONNECTICUT, A CORPORATION.

DESIGN FOR AN ELASTIC WEBBING.

45,167.

Specification for Design.

Patented Jan. 20, 1914.

Application filed November 3, 1913. Serial No. 799,036. Term of patent 14 years.

To all whom it may concern:

Be it known that I, FRANK H. FRISSELL, a citizen of the United States, residing at Middletown, in the county of Middlesex and State of Connecticut, have invented a new, original, and ornamental Design for Elastic Webbing, of which the following is a specification, reference being had to the accompanying drawing, forming part thereof.

The figure is a face view of a piece of elastic webbing showing my new design.

I claim:

The ornamental design for elastic webbing, as shown.

FRANK H. FRISSELL.

Witnesses:

B. E. BLENUS,
A. S. PRATT.
